ABSTRACT OF THE DISCLOSURE

Apparatus for use by electricians, heating, air-conditioning and ventilating contractors and the like is provided in order to transfer location markings interpolated from blueprints to actual markings on the floor of the building to the ceiling as disclosed. A tube is supported from the floor in such manner that the tube is vertically aligned and its vertical axis is accurately located in line with a floor marking. One means to transfer the floor marking to the ceiling is by light transmission. A bulb is supported in the tube and light emitted therefrom is focused on the ceiling. Light from the bulb passes through a crosshair located centrally of the axis of the tube and such crosshair is projected onto the ceiling. The workman marks on the ceiling the location of the crosshair which is in vertical alignment with the floor marking. Illumination of the bulb may be from a conventional electrical outlet, from a flashlight battery, or by a blinker circuit. Alternatively, a compressed air gun may be located in the tube and a pellet containing a dye propelled from the gun onto the ceiling where it leaves a mark.

This invention relates to a new and improved apparatus for transferring markings from a floor to a ceiling location. In building construction and repair, it is frequently necessary to mark a spot on a ceiling in accordance with an architect's plans for the specific location of an electrical outlet, lighting fixture, heating, ventilating or air-conditioning duct, or the like.

Conventionally, workmen lay out the location of such markings on the floor. Transmission of the marking to the ceiling is a labor-consuming job usually requiring two men and the accuracy of the location is difficult to obtain, particularly when a strong wind is blowing, which interferes with the accuracy of the plumb bob conveniently employed for such purpose. Accordingly, it is a principal object of the present invention to reduce the time and labor required to transmit markings from the one location to the other, and also to improve the accuracy of such transmission.

Another object of the invention is to provide a light-weight, readily portable, inexpensive tool which may be used for the purpose stated. Operation of the tool is simple and does not require special training or skill.

A still further feature of the invention is the provision of a tool which is relatively fool-proof and not readily subject to damage or misalignment.

Other objects of the present invention will become apparent upon reading the following specification and referring to the accompanying drawings in which similar characters of reference represent corresponding parts in each of the several views.

In the drawings:

FIG. 1 is a perspective view of one modification of the present invention showing the tool used to transmit a marking from the floor to the ceiling.

FIG. 2 is an enlarged top plan of the structure of FIG. 1.

FIG. 3 is an enlarged vertical sectional view through a portion of the tube.

FIG. 4 is a view similar to FIG. 3 showing a modification.

2

FIG. 5 is a view similar to FIG. 3 of still another modification.

FIG. 6 is a schematic circuit diagram of the modification of FIG. 5.

FIG. 7 is a perspective view of a still further modification of the invention.

FIG. 8 is a vertical sectional view of still another modification employing an air gun.

FIG. 9 is an enlarged fragmentary vertical sectional view through the gun of FIG. 8, said view being partially schematic.

As best shown in FIG. 1, a marking 11 has been laid out on the floor in accordance with a plan, and the purpose of the use of the tool here described is to transmit said marking 11 to a spot 12 on the ceiling which is accurately vertically above mark 11. In the form of the invention shown in FIGS. 1-3, a tube 13 has a sleeve 14 on the lower end accurately aligned with the central axis of the tube. Sliding in sleeve 14 is rod 16 carrying on its lower end a plumb bob 17 which is, in use of the instrument, accurately located above the mark 11. Tube 13 is supported in vertical alignment by a stand 21 here shown to have a horizontal ring 22 supported above the floor by a plurality of legs 23, here shown to be three in number. Within ring 22 is a gimbal arrangement consisting of an inner ring 24 supported from ring 22 by horizontal rods 26. Accurate, substantially friction-proof bearings (not shown) support ring 24 on rod 26. At right angles to rods 26 are second rods 27, the inner ends of which are attached to tube 13 and the outer ends of which are journaled in accurate bearings (not shown) in ring 24. The weight of plumb bob 17 maintains tube 13 in vertical position because of the gimbal-like support and regardless of the evenness of the floor or the accuracy of the length of legs 23. Accordingly, it is assumed that the central axis of tube 13 is vertical and directly in line with marking 11.

The electrical and optical arrangement of the modification of FIGS. 1-3 is best shown in FIG. 3. A source of electric current, such as household current, is plugged into lead wires 31 which run up one of the legs 23 and are affixed at the top by a clamp 32 leaving a loop 33 of highly flexible wire extending up into tube 13. Thus, the weight and stiffness of the lead wire does not tend to force tube 13 out of vertical alignment. It will further be noted that the point 34 at which the lead wires enter the tube 13 is at the level of the gimbal mounting or close thereto. The flexible wires 33 terminate inside tube 13 in a terminal box 36. The switch 37 may be located remote from support 21 so that turning the switch on and off does not affect the accuracy of alignment of tube 13. Within tube 13 is a bulb 35, the socket 38 of which is connected to terminal 36 by wires 39. Below bulb 35 is a parabolic reflector 41 which reflects the light of bulb 35 upward. A condenser lens 42 directs the rays of light in a straight line. Since the heights of ceilings vary, a focusing tube 43 may be used, telescoping within tube 13. A rack 44 is formed on the exterior of tube 43 engaged by a pinion 46 supported on tube 13 by bracket 47. By turning pinion 46, the tube 43 may be moved in and out relative to tube 13. A focusing lens 48 is installed in the upper end of tube 43. In the bottom of tube 43 is a slide 49 to which is fixed a crosshair 51. Other means may be used to locate the crosshair or other indicia. The effect of lenses 42 and 48 as adjusted by pinion 46 is to focus the image of the crosshair 51 on the ceiling to display mark 12.

In use, the plumb bob 17 is centered relative to mark 11, switch 37 turned on, and pinion 46 moved until the spot 12 is accurately focused on the ceiling. Since the tube 13 is in accurate vertical position, the mark 12 is accurately located in vertical alignment with mark 11. The workman

then mounts a ladder and marks the image 12 on the ceiling.

FIG. 4 shows a construction similar to FIGS. 1-3 except that a battery 56 is installed in the bottom of tube 13a, the battery being changed by removal of a plug 57 in the bottom of the tube to which sleeve 14a is attached. Switch 37a is installed on tube 13a, or remote therefrom. In other respects, the construction of FIG. 1 is similar to that previously described and the same reference numerals followed by the subscript *a* are used to designate corresponding parts.

FIG. 5 is similar in construction to FIG. 4 except that the light 35b flashes intermittently. The electrical circuit for the flasher is shown in FIG. 6, it being understood that such circuit is one of many which may be employed and is of a type used commercially in highway flasher warning lamps.

Specification of components of the circuit of FIG. 6 is as follows:

TABLE 1

B56b	—6 v.
R ₁	—1200 ohms
R ₂	—330K
C	—3 mfd.
Q ₁	—4JD2A10
Q ₂	—2N188A
L35b	—GE No. 1850

The other parts correspond to the previous modifications and the same parts are indicated by the same reference numerals followed by the subscript *b*.

FIG. 7 illustrates an alternative means for holding the tube 13c in vertical alignment. A base plate 61 is formed with a central aperture 62 through which the marking 11b may be observed. A pair of bubble sights 63 is mounted on plate 61 at right angles to each other. At the corners of plate 61 are three or more adjustable legs 64 threaded into tapped holes in plate 61. By adjustment of leg screws 64, the bubbles 63 may be brought into the centers of their respective mountings indicating that plate 61 is horizontal. Fixed to plate 61 are legs 66 which are in turn fixed at their opposite ends to tube 13c. The illumination of the apparatus may be in accordance with any of the means previously described in FIGS. 1-5, inclusive, or other means. Focussing of the light is accomplished in a similar manner and corresponding parts are indicated by the same reference numerals followed by the subscript *c*. As a means of locating the central axis of tube 13c over mark 11c, a pointer 67 which may be a steel rod or the like is fixed to the bottom of tube 13c directly below its axis. The lower end of rod 67 is aligned with mark 11c.

FIGS. 8 and 9 show an alternate means for transmitting the marking to the ceiling. Tube 13d is accurately held in vertical position by the means shown in FIG. 1 or, alternatively, by the means shown in FIG. 7. The same reference numerals followed by the subscript *d* are used to designate corresponding parts. The propelling means is by a compressed air or compressed carbon dioxide capsule 71 contained in a chamber 72 in tube 13d. An abutment 73 limits inward movement of the capsule. The cap 74 on the bottom of tube 13d to which eye 14d is attached has a pin 76 on its interior which penetrates the lower end of capsule 71 allowing the compressed gas to fill chamber 72. An elongated bore 77 is formed in the upper end of tube 13d, and said bore may be rifled if desired. The lower end 78 of bore 77 is of constricted diameter to provide a shoulder 79 against which a felt or other suitably fabricated ball 81 may be forced as by a ramrod (not shown). Preferably ball 81 is impregnated with a dye. A trigger arrangement is shown more or less schematically in FIG. 9, it being understood that such trigger arrangement is subject to wide modification and may resemble that of compressed air B-B gun. In the simple system shown, a trigger lever 82 is pivoted by pin 83 to bracket 84 attached to tube 13d. A flexible cable 86

is connected to lever 87 on lever 82. By pushing the plunger 88 at the opposite end of flexible cable 86, the lever 82 may be pivoted from the solid line position shown in FIG. 9 to the dotted line position. Connected to the lower end of lever 82 is a slide 91 which, when in the position shown in solid lines in FIG. 9, closes off communication between chamber 72 and restricted diameter bore 78. Connected to the upper end of lever 82 is a second slide 92 which closes off the bore 77 immediately above pellet 81. Slides 91 and 92 reciprocate in tube 13d in suitable transverse slots. Pellet 81 is loaded into bore 77 from the top when the slides 91, 92 are in the position shown in FIG. 9. Thereupon, the plunger 88 is pressed, closing the slide 92 and opening the slide 91 so that the bore 78 behind pellet 81 is pressurized from the capsule 71. When the plunger 88 is released, spring 93 acting on lever 82 returns the slides 91, 92 to the position shown in FIG. 9 whereupon the pressure behind pellet 81 propels it up to the ceiling and the dye impregnated therein leaves a mark on the ceiling. The slide 91 has meanwhile closed off the chamber 72 to conserve gas.

What is claimed is:

1. Apparatus for use in transferring a mark on a floor to a point on the ceiling directly above said mark comprising a casing, a gimbal in which said casing is mounted, a plumb bob depending from said casing in line with the longitudinal axis of said casing, the weight of said plumb bob holding said casing vertical and in line with said mark, a light bulb in said casing aligned with said axis for projecting along a prolongation of said axis onto said ceiling an intelligible indicator of said mark, a battery centered along the axis of said casing, a blinker electric circuit interposed between said battery and said light bulb whereby energization of said light bulb is intermittent and energy of said battery is conserved, said circuit including a condenser and means for discharging said condenser, and focusing means for focusing beams of light on the ceiling and an image screen between said light bulb and focusing means, said image screen having a mark which is projected onto the ceiling.

2. Apparatus according to claim 1, which further comprises a sleeve on the bottom end of said casing and a rod slidably in said sleeve aligned with said axis, said plumb bob located on the lower end of said rod, said rod extensible relative to said gimbal until said plumb bob contacts said mark on said floor.

3. Apparatus for use in transferring a mark on a floor to a point on the ceiling directly above said mark comprising a casing, a gimbal in which said casing is mounted, a plumb bob depending from said casing in line with the longitudinal axis of said casing, the weight of said plumb bob holding said casing vertical and in line with said mark, a compressed gas gun, said gun located within said casing and having a bore in alignment with said axis, a chamber at the bottom of said bore shaped to receive a projectile, a source of compressed gas for said gun located in said casing, valve means cutting off communication between said source and said chamber, and an externally operated trigger means for opening said valve means to project said projectile out of said chamber along said bore in line with said axis.
